UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

FEEDING AND FORMING BOX MACHINE.

Application filed January 29, 1926. Serial No. 84,572.

This invention relates to the production of cylindrical or tubular articles, such as paper boxes and paper cans, and refers particularly to the production of such articles having end 5 disk closures.

The object of the invention is to produce such articles at high speed and in an economical manner, especially with the bodies or cylindrical portions accurately formed.

10 With said object in view, the invention consists in the construction and combination of parts substantially as hereinafter described and claimed.

Of the accompanying drawings:

15 Figure 1 is a side elevation, partly broken out, of so much of the machine as is necessary to illustrate the invention.

Figure 2 is an elevation from the right of Figure 1, on a smaller scale, and omitting 20 some portions of the machine.

Figure 3 is a view similar to a portion of Figure 1, on a larger scale to better illustrate some of the details.

Figure 4 is a view looking in the direction 25 of the arrow 4 at the right of Figure 3.

Figure 5 is a detail plan view hereinafter referred to.

Figure 6 is a perspective view of a paper receptacle made by the machine.

30 Similar reference characters designate similar parts or features in all of the views.

12 represents a base plate supporting the other portions of the machine, including side walls 13. Supported by the side walls 13 is 35 a hopper 14 for a pile of the blanks or strips indicated at *a* (Fig. 1), said hopper having a front wall or gate strip 15, below which, and suitably spaced therefrom, is a feed wheel 16. Another feed wheel 17 may be 40 employed, if desired.

Extending forward from the side wall 14 of the hopper and preferably integral therewith is a side guide 18. The bottom member or floor 19 of the hopper extends forward 45 nearly as far as the side guide 18 and is formed with suitable slots or openings for the operation of the feed wheels. It also has an opening 20 for the roll 21, which acts as an auxiliary feed for the strips *a* fed from 50 the hopper.

Mounted on a cross bar or pin 22 is an arm 23, carrying a pin 24 on which a roll 25 is mounted (Figs. 1 and 5).

Also mounted on the pivot pin 22 is an arm

26 (Figs. 1, 3 and 5), having a slotted plate 55 27. Secured to the plate 27 and projecting down through slots 28 thereof, are fingers 29, preferably resilient.

Each bottom blank *a* advanced from the hopper, is forwarded by the auxiliary feed 60 roll 21 over the glue applying device, which consists of a disc 30 carried by a shaft 31, said shaft having also an arm provided with a transverse gluing pad 32. This compound gluing device receives glue from a roll 33 65 mounted to rotate in a glue pot 34, a suitable scraper for the glue roll being provided at 35.

The rotary members so far described, are connected by suitable gearing, not necessary 70 to illustrate in detail, so that they will perform their operations, the glue roll 33 transferring glue to the disc 30 and to the pad 32 so that during each revolution of the shaft 31, the disc 30 will apply a stripe of glue 75 along one edge of the blank *a* while the pad 32 will apply a transverse area of glue to the under surface of the rear edge of the blank *a* passing over it.

Mounted on the side guide 18 (Figs. 1, 3 80 and 4), is a slide 36 connected by a link 37 with a lever 38, which is actuated by any suitable means to reciprocate the slide 36 the proper distance.

Depending from the forward end of the 85 slide 36, is a bracket or lug 39 to which is pivoted at 40 the hub 41 of a pushing blade 42 which moves along the long slot illustrated in Figure 5 as formed in the arm 26 and plate 27. Projecting from the upper 90 side of the hub 41 is a lug 43, adapted to contact, when the slide moves rearwardly to the position indicated in Figures 1 and 3, with a fixed stop 44 projecting from the side guide 18. Projecting from the lug 39 is a 95 small stop pin 45. A spring 43' connected to a pin 41' of the hub 41, tends to hold the lug 43 in contact with the fixed stop 44, when the slide is in its rearward position so that the pushing blade 42 will be swung somewhat 100 upward as shown in Figure 1. When, however, the slide moves forward, which occurs after a blank *a* has been carried forward far enough so that its rear edge is substantially beyond the nip of the roll 21 and discs or rolls 105 25, the moment that lug 43 leaves the stop 44, the spring acts upon the pin 41' of the hub 41 of the pushing blade, to swing the

latter down to a substantially vertical position, as illustrated by dotted lines in Figure 1, the limit of such movement being determined by the stop pin 45 with which the pin 41' would then contact.

Suitably mounted on the frame of the machine, is a cylindrical chamber 46, having a tangential slot 47 in position for the forward end of a blank *a* which is being pushed forward to enter the chamber so that as the strip or blank is completely advanced by the pushing blade 42, the said strip or blank will be guided by the inner wall of the chamber so as to be bent into a perfect cylindrical form, the length of the strip or blank, slightly exceeding the internal diameter of the cylindrical chamber so that the ends of the strip or blank will be overlapped when it has been completely bent to cylindrical form.

As has been described, the rear end of the strip has received glue across the surface of its rear edge. Therefore, when the blank has been completely bent to cylindrical form, its upper, glue carrying surface over-laps the upper surface of what was the forward end of the strip.

Mounted at 48, is a presser 49, having a rearwardly extending arm 50 to which is connected a link 51 which is operated by any suitable means to oscillate the presser 49 at the proper times. Such operation of the presser is so timed that the presser is in the upwardly swung position indicated by dotted lines in Figure 1, when the blank is being fed through the slot 47. The under surface of the presser is curved practically concentrically with the wall of the chamber 46, thereby serving two purposes, namely, first, the curved under-surface acts as a guide for the forward edge of the blank, being pushed through the slot, and then, after the blank has been completely inserted in the cylindrical chamber and the ends over-lapped, the presser is actuated downwardly. Its curved under-surface fits the over-lapping curved portions of the blank and assures uniform pressure over that glued area.

Referring now to Figure 2, we illustrate at the right a standard 52, in which is reciprocally mounted the stem 53 of a mandrel 54, said mandrel being preferably constructed so that it can be expanded. The mandrel is so mounted and actuated that it will enter the cylindrical chamber 46 either before or after the blank has been completely inserted in the cylindrical chamber.

At the left of Figure 2, we illustrate a standard 55 in which is reciprocally mounted the stem 56 of a plunger disc 57, the diameter of which is such as to enable it to enter one end of the cylindrical chamber as presently described. Preferably the plunger 57 has a rib or slight flange 58.

Suitably supported by the frame of the machine, is a guide 59 in which the end discs

b are adapted to be fed at the proper times, so that one disc will arrive against a suitable stop 60 indicated by dotted lines in Figure 1 and in position so that when the plunger disc 57 is actuated to the right (Figure 2), it will force the disc *b* into the end of the cylindrically bent blank *a* in the chamber 46 (see Figure 6). To properly size the disc *b* and bend its margin in a sort of a crimped manner, the end of the chamber 46 is provided with a suitable sizing guide 61. Of course the operation just described brings the margin of the disc into contact with the glue which has been applied along one edge of the bent blank *a*.

It is to be understood of course, that when the plunger disc 57 operates as described, the mandrel 54 is in its extreme inner position in the cylindrical chamber 46, so that during the pushing action of the disc 57, the inner end of the mandrel 54 determines the distance to which the disc *b* can be pushed, while the ledge 54' of the mandrel 54 arrests the outer edge of the bent blank so that the bent blank itself is not pushed out of the cylindrical chamber.

After the parts have been formed and assembled as described, the mandrel 54 retreats to its outward position as illustrated by Figure 2, and the stem 56 of the plunger disc is actuated so that said plunger disc will push the completed article out of the cylindrical chamber and towards the right so that it can drop on to any suitable delivery chute 62.

If the glue which has been applied as described is insufficient to hold the disc *b* in place for all purposes to which the boxes are to be applied, any suitable crimping implement or mechanism may be employed to crimp the margins of the discs and the surrounding edges of the tubes together.

Having now described our invention, we claim:—

1. In a machine of the character described, a hollow normally empty former having an opening, and means for pushing a blank through said opening to cause it to automatically partake of the shape of the inner wall of said former.

2. In a machine of the character described, a forming member having a cylindrical wall provided with a slot, and means for pushing a blank completely through said slot to cause it to automatically bend to cylindrical form.

3. In a machine of the character described, a hollow former having an opening, means for pushing a blank of the proper length completely through said opening to cause it to automatically partake of the shape of the inner wall of the former, and means for securing the end portions of the blank together.

4. In a machine of the character described, a hollow former having an opening, means for pushing a blank of the proper length completely through said opening to cause it to conform to the shape of the inner wall of

the former with the ends of the blank overlapped, means for applying adhesive to an end portion of the blank on its way to the former, and means for pressing the overlapped ends together.

5. The combination with a cylindrical chamber having a slot, of means for pushing blanks successively completely through said slot to cause them to automatically bend to cylindrical form with overlapped ends, and means for placing end pieces in the bent blanks while in said chamber.

10. The combination substantially as specified by claim 5, a mandrel being provided with means to determine the inward location of said end pieces.

15. The combination with a cylindrical chamber having a slot, of a mandrel movable

into and from one end of the chamber, a plunger movable to and from position inside 20 the other end of the chamber, means for pushing a blank through the slot of the chamber to cause it to bend to cylindrical form with overlapped ends, and means for locating a disc in position to be pushed by said plunger 25 into the bent blank in the chamber.

8. The combination substantially as specified by claim 7, means being provided for applying adhesive to the blank to effect adhesion of the overlapped ends of the blank 30 and of the margin of the inserted disc.

In testimony whereof we have affixed our signatures.

LEON E. LA BOMBARD.
MELVIN H. SIDEBOTHAM.
